US00D612365S

(12) **United States Design Patent**
Lin

(10) **Patent No.:** US D612,365 S
(45) **Date of Patent:** ** Mar. 23, 2010

(54) **MULTI-FUNCTIONAL REMOTE
CONTROLLER**

(75) Inventor: **Chung-Hung Lin**, Syuejia Township,
Tainan County (TW)

(73) Assignee: **Jow Tong Technology Co., Ltd.**, Tainan
Hsien (TW)

(**) Term: **14 Years**

(21) Appl. No.: **29/347,125**

(22) Filed: **Sep. 28, 2009**

(51) **LOC (9) Cl.** 14-03

(52) **U.S. Cl.** D14/218

(58) **Field of Classification Search** D14/218,
D14/455, 138; D13/168; D21/566; D10/104,
D10/106; 345/169; 348/14.05, 114, 211.99,
348/734; 340/825.24, 825.69; 341/22; 455/92,
455/95, 128, 151.1–151.4, 352, 355, 121 FOR;

(57) **CLAIM**

The ornamental design for a multi-functional remote controller, as shown and described.

DESCRIPTION

FIG. 1 is a perspective view of a multi-functional remote controller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
